UNITED STATES PATENT OFFICE

171,731

COMBINED HEATER, VENTILATOR, AND DEFROSTER UNIT

Leonard R. Phillips, East Hartford, and William J. Waeldner, Farmington, Conn., assignors to Anemostat Corporation of America, New York, N. Y., a corporation of Delaware

Application July 3, 1953, Serial No. 25,788

Term of patent 14 years

(Cl. D14—6)

To all whom it may concern:

Be it known that we, Leonard R. Phillips and William J. Waeldner, both citizens of the United States of America, residing, respectively, at East Hartford, Connecticut, and Farmington, Connecticut, have invented a new, original, and ornamental Design for Combined Heater, Ventilator, and Defroster Unit, of which the following is a specification, reference being made to the accompanying drawings forming a part hereof.

Figure 1 is a left front corner perspective view of a combined heater, ventilator, and defroster unit, showing our new design;

Figure 2 is a top plan view;

Figure 3 is a right rear corner perspective view; and

Figure 4 is a right front corner perspective view thereof.

We claim:

The ornamental design for a combined heater, ventilator, and defroster unit, as shown.

LEONARD R. PHILLIPS.

WILLIAM J. WAELDNER.
